UNITED STATES PATENT OFFICE

MARIO DESERVI, OF OAKLAND, CALIFORNIA

DESIGN FOR AN AUTOMOBILE

Application filed July 13, 1931. Serial No. 40,531. Term of patent 14 years.

To all whom it may concern:

Be it known that I, MARIO DESERVI, a citizen of the United States and a resident of Oakland, in the county of Alameda and State of California, have invented a new, original, and ornamental Design for an Automobile, of which the following is a specification, reference being had to the accompanying drawings, forming part thereof.

I claim:

The ornamental design for an automobile substantially as shown.

MARIO DESERVI.
